UNITED STATES PATENT OFFICE.

LEONARD LEE LEFLER, OF HAYTI, MISSOURI.

PENCIL-HOLDER.

1,321,831.

Specification of Letters Patent.

Patented Nov. 18, 1919.

Application filed May 9, 1919. Serial No. 295,894.

To all whom it may concern:

Be it known that I, LEONARD LEE LEFLER, a citizen of the United States, and a resident of Hayti, in the county of Pemiscot 5 and State of Missouri, have invented certain new and useful Improvements in Pencil-Holders, of which the following is a specification.

This invention relates to an improvement 10 in pencil holders, and one of the principal objects thereof is to provide a pencil holder which will allow the pencil to be used up almost entirely, even though the pencil is too short to be comfortably held in the 15 hand.

A further object of the invention is to provide an improved pencil holder which will be extremely simple, durable, efficient in operation and inexpensive to manufacture.

With these and other objects in view, which will become apparent as the description proceeds, the invention resides in the construction, combination and arrangement 20 of parts hereinafter more fully described and claimed, and illustrated in the accompanying drawing in which like characters of reference indicate like parts throughout the several figures of which:

Figure 1 represents a side elevational view 25 of a pencil holder constructed according to my invention, showing the same positioned on a new pencil.

Fig. 2 represents an elevational view at right angles to Fig. 1, showing the pencil as 30 having been practically used up.

Fig. 3 represents a longitudinal sectional view on the line 3—3 of Fig. 2.

Referring more particularly to the drawing, the holder includes a tube 1 made of 40 brass or other suitable metal, having its upper and lower ends 2 and 3 respectively slightly tapered. These ends are bifurcated, each having V-shaped slots 4 cut in the metal, at diametrically opposed points, the 45 inner ends of these slots terminating in round openings 5, whereby to prevent splitting of the tube, and whereby to assist in rendering the tongues or jaws formed by the bifurcations resilient.

The upper end of the holder is circumferentially channelled as at 6 for the purpose 50 of strengthening the upper jaws, and for the purpose of receiving the flanges 7, ordinarily formed on the eraser holders of pencils. 55 This channel occurs intermediate the ends of the upper jaws as will be noted.

One of the upper jaws is extended and pointed downwardly and inwardly to form a clip 8 whereby the pencil holder may be retained in the pocket of the user against 60 accidental displacement.

In operation, when the holder is used with a new or long pencil, the pencil is inserted in the holder from the upper end toward the lower end. Until the pencil is 65 worn down, the holder will simply serve as a means of preventing the pencil from loss from the user's pocket. However, when the pencil is worn so that it becomes of a length substantially equal to that of the holder or 70 shorter, the top of the pencil, including the eraser holder, may be cut off with a pocket knife and pushed in between the upper jaws of the holder, until the flanges 7 engage in the channel 6. The lower or pointed end 75 of the pencil, may then be inserted in the lower end of the holder. As the pencil is used from time to time it may be drawn out and sharpened.

By the use of the holder I have provided, 80 pencils may be used up almost entirely. Even though the pencil is only a couple of inches or less in length it may still be used. The holder will not only retain the short piece firmly but will permit writing with 85 ease. Not only will it serve in this manner to economize in the use of pencils, but it will be found as before mentioned, of great use in preventing the loss of pencils from the pockets of the users, and also of use in protecting 90 the pencil point when not in use by slipping the holder down over the point.

Although I have described the preferred embodiment of my invention, I may desire to make such changes in the construction, 95 combination and arrangement of parts thereof, as do not depart from the spirit of the invention and the scope of the appended claims.

I claim:

1. A pencil holder comprising a tubular body having its upper and lower ends bifurcated and tapered whereby to provide resilient jaws for receiving respectively the eraser end and the pointed end of the pencil, one of said upper jaws being extended and bent downwardly and inwardly against the body to provide a clip, substantially as described.

2. A pencil holder comprising a tubular body having one end provided with resilient pencil engaging jaws, one of said jaws being

relatively long and being bent backwardly and inwardly into engagement with the tubular body whereby to form a holding clip.

3. A pencil holder comprising a tubular body having one end tapered and bifurcated whereby to provide pencil engaging clamping jaws, one of said jaws being relatively long and being bent upon itself into engage-

ment with the body whereby to provide a holding clip.

4. A tubular pencil holder having tapered resilient jaws for receiving the pencil, one of the jaws being extended and bent inwardly against the holder for forming a clip.

LEONARD LEE LEFLER.
